UNITED STATES PATENT OFFICE.

CHARLES WILLIAM RIPSCH AND JAMES C. DAWLEY, OF DAYTON, OHIO, ASSIGNEES TO
THE JOYCE-CRIDLAND COMPANY, OF DAYTON, OHIO, A CORPORATION OF OHIO.

POSITIVE STOP FOR LIFTING JACKS.

Application filed July 12, 1921. Serial No. 484,200.

To all whom it may concern:

Be it known that we, CHARLES W. RIPSCH and JAMES C. DAWLEY, citizens of the United States, residing at Dayton, in the county of Montgomery and State of Ohio, have invented certain new and useful Improvements in Positive Stops for Lifting Jacks, of which the following is a specification, reference being had therein to the accompanying drawing.

This invention relates to lifting jacks or the like.

One object of the invention is to provide means for limiting the movement of the lifting member of a jack or the like relatively to the standard so as to prevent the lifting member from being run out of the standard and to prevent the standard from running off the lifting member and out of the housing when the jack as a whole is lifted from the ground.

A further object of the invention is to provide means for securing the nut to the standard.

25 A further object of the invention is to provide means for detachably securing the nut to the standard and for automatically disconnecting the same when the lifting element has been elevated to a predetermined height.

Other objects of the invention will appear as the device is described in detail.

In the accompanying drawings Fig. 1 is a sectional view, partly in elevation, of a jack embodying our invention; Fig. 2 is a plan view of the nut and the standard; Fig. 3 is a vertical sectional view of the upper end of the standard, taken on the line 3—3 of Fig. 1; Fig. 4 is a vertical section of a modified form of the upper end of the standard and nut showing the lifting element near the upper limit of its movement; Fig. 5 is a perspective detail view of the locking flange; and Fig. 6 is a perspective view of the upper end of the standard and nut.

45 In these drawings the invention is illustrated as applied to a self lowering jack of a known construction but it will be understood that the invention may be applied to jacks of various kinds and that the invention itself may take various forms without departing from the spirit thereof.

As here shown, the jack comprises a base 1 from which there extends an upright hollow standard 2 having mounted in its upper

end a nut 3 in which the lifting element 4 is screw threaded. The lifting element supports at its upper end a cap, or work engaging member, 5 to which is secured a housing 6 extending downwardly therefrom and embracing the standard 2. The cap 5 and housing 6 are rotatably supported on the lifting element and, as here shown, a ball bearing 7 is interposed between the cap and the flat upper surface of a beveled gear 8 which is rigidly secured to the lifting element. The beveled gear 8 meshes with a second beveled gear 9 secured to a shaft 10 journaled in the side of the housing 6 and having connected with its outer end suitable actuating devices, such as a ratchet wheel 11 and a lever 12 carrying a pawl 13 to cooperate with the ratchet wheel 11. The jack is also provided with suitable devices for controlling the downward movement of the load but as these do not enter into the present invention they need not be herein described.

50 In order to positively limit the movement of the lifting element relatively to the standard the latter is provided near its upper end with a laterally extending projection, or flange, arranged in the path of an inwardly projecting shoulder 14 carried by the standard near the lower end thereof. The stop at the upper end of the standard may take various forms but preferably consists of a flange secured to the standard and extending laterally beyond the edge thereof. In that form of the device shown in Figs. 1 to 3 the flange is shown at 15 as rigidly secured to and preferably formed integral with the nut 3, the flange resting upon the upper edge of the standard and the nut being secured to the standard in any suitable manner as by means of a screw 16 extending through an opening 17 in the side of the standard and into the nut, thus holding the nut against vertical displacement, the rotary strain on the nut being taken up by other means to be hereinafter described. To prevent strain being imposed upon the screw 16, the opening 17 is slightly larger than the head of the screw.

55 It is highly essential that a very strong, rigid connection should be provided between the nut and the standard to prevent the nut from rotating in the standard during the operation of the jack. This has been accomplished heretofore by providing the standard with lugs extending through re-

cesses in a part carried by the nut and overlapping the same, but this has been found objectionable for various reasons, one of the principal of which is the liability of the 5 lugs to break off. In the present construction, this connection is established by providing the standard in its upper edge with one or more notches, or recesses, 18 and securing to the nut a part having lugs adapted to enter these notches and thus rigidly and very strongly hold the nut against rotation. In Figs. 1 to 3 the lugs are shown at 10 19 as formed integral with the flange 15 and the nut.

15 If desired, the flange may be formed separately from both the nut and the standard and as shown in Figs. 4, 5 and 6, the flange comprises a separate member, or collar, 20 which rests upon the upper edges of the 20 standard and nut, and in this form of the device the nut is provided with one or more notches, or recesses, 21 adapted to register with the corresponding recesses 18 in the standard. The collar 20 carries lugs 22 25 adapted to extend into the registering notches 18 and 21 of the standard and nut, thus securing the nut against rotation in the standard.

The collar, or flange, 20 may be connected 30 with the nut and the standard in any suitable manner. In the present instance it is secured to the upper edge of the standard by screws 23 which extend through the flange and are threaded into the edge of the 35 standard. The inner edge of the collar overlaps the nut and thus establishes the necessary connection between these parts. In this manner the flange is retained in position solely by the screws and in the event 40 of excessive pressure is applied to the flange the screws will yield. Ordinarily the threads will be stripped therefrom, thus disconnecting the parts and preventing breakage of the mechanism. While the screws 45 establish a connection between the flange and the standard which has ample strength under all normal conditions of operation they at the same time provide a point of least strength which under abnormal conditions will yield, thus protecting the other 50 parts of the mechanism from injury.

While we have shown and described one embodiment of our invention we wish it to be understood that we do not desire to be limited to the details thereof as various 55 modifications may occur to a person skilled in the art.

Having now fully described our invention what we claim as new and desire to secure by Letters Patent is:

1. In a mechanism of the character described, a standard, a nut mounted in said standard, a lifting element screw threaded into said nut, a housing carried by said lift-

ing element embracing said standard and 65 having a shoulder near the lower end thereof, and a flange secured to said nut and said standard and projecting beyond the edge of said standard into the path of said shoulder.

2. In a mechanism of the character described, a standard, a nut mounted in said standard, a lifting element screw threaded into said nut, a housing carried by said lifting element, embracing said standard and 70 having a shoulder near the lower end thereof, a flange permanently secured to said nut and extending laterally beyond the edge of said standard into the path of said shoulder, and means carried by said flange for holding 75 said nut against rotation in said standard.

3. In a mechanism of the character described, a standard, a nut mounted in said standard, a lifting element screw threaded into said nut, a housing carried by said lifting element, embracing said standard and 80 having a shoulder near the lower end thereof, a flange formed integral with said nut and extending beyond the outer edge of said standard into the path of said shoulder, and 85 interlocking parts carried by said nut and said standard to hold the nut against rotation 90 in said standard.

4. In a mechanism of the character described, a standard having a notch in its 95 upper edge, a nut mounted in said standard, a lug connected with said nut and adapted to enter said notch, means for attaching said nut to said standard, a lifting element screw threaded into said nut, and means for operating 100 said lifting element.

5. In a mechanism of the character described, a standard having a notch in its upper edge, a nut mounted in said standard, a flange connected with said nut, overlapping the edge of said standard and having 105 a lug adapted to enter said notch, a lifting element screw threaded into said nut, and means for actuating said lifting element.

6. In a mechanism of the character described, a standard having a notch in its upper edge, a nut mounted in said standard and having a lug adapted to enter said notch, a screw extending through the side wall of said standard into said nut, a lifting element screw threaded into said nut, and means for actuating 110 said lifting element.

7. In a mechanism of the character described, a standard having a notch in its 115 upper edge, a nut mounted in said standard, a flange connected with said nut, overlapping the edge of said standard and having a lug adapted to enter said notch, a screw extending through the side wall of said standard into said nut, the opening in the standard through which said screw passes being larger than the head of the screw, a 120

lifting element screw threaded into said nut, and means for actuating said lifting element.

8. In a mechanism of the character described, a standard having a notch in its upper edge, a nut mounted in said standard, a flange connected with said nut, extending beyond the edge of said standard and having a lug to enter the notch in said standard, a lifting element screw threaded

into said nut, and a part connected with said lifting element and arranged to engage the edge of said flange to limit the relative movements of the lifting element and the standard.

15

In testimony whereof, we affix our signatures hereto.

CHARLES WILLIAM RIPSCH.
JAMES C. DAWLEY.
